UNITED STATES PATENT OFFICE.

WILLIAM JAMES PENFOLD, OF BRUNSWICK, VICTORIA, AUSTRALIA.

MANUFACTURE OF SERUMS FROM ANIMALS, EXCLUDING MAN.

1,378,896.

Specification of Letters Patent.

Patented May 24, 1921.

Application filed September 14, 1920. Serial No. 410,204.

To all whom it may concern:

Be it known that I, WILLIAM JAMES PENFOLD, a subject of the King of Great Britain, residing at Park street, Brunswick, in the 5 State of Victoria, Commonwealth of Australia, bacteriologist, have invented certain new and useful Improvements in the Manufacture of Serums from Animals, Excluding Man, of which the following is a specification.

This invention relates to certain improvements in the manufacture of serums from animals, excluding man, and refers more especially to the production of serums which 15 are obtained from animals which have been rendered immune, to bacteria or their toxins. This invention, however, is not confined to the production of anti-toxic or anti-bacterial serums but may be applied to the production 20 of other serums.

In the production of serums as at present practised it is customary to extract the blood from an animal (generally the horse) which has or has not been rendered immune and this blood is treated for the separation of the 25 serum therefrom.

The separation of the serum is customarily effected in either of several ways:

1. By receiving the blood into a jar or 30 flask in which it is allowed to clot and then expressing the serum therefrom by suitable pressure. In this method the red cells of the blood are permanently entangled in the clot.

2. By receiving the blood into bottles or 35 flasks containing a solution of oxalate or sodium citrate or some other anti-clotting agent, and allowing the blood to stand therein so that its cellular elements sediment and the supernatant plasma can be removed into 40 other containers. This plasma is then clotted by the addition of a lime salt and the serum is expressed from the clotted plasma by suitable pressure.

45 3. By receiving the blood into containers coated with paraffin or some other like substance which prevents clotting, allowing the cellular elements to settle, withdrawing the supernatant plasma, which is then clotted, and subsequently separating the serum from the clot.

All these methods however, have the grave disadvantage that they produce profound anemia, so that after a first bleeding 50 of eight to ten liters in the case of a horse, for example, a week's interval should be al-

lowed before a second bleeding is undertaken. This week's interval is by no means sufficient to allow of complete recovery from the anemia. A horse may be bled in this 60 way each week, but if the bleeding be to the extent above indicated the animal becomes progressively more anemic, so that after two, three or four bleedings, it is necessary to give it a prolonged rest. This rest 65 usually consists of one week for every individual bleeding, that is to say, if the horse has been bled every week for four weeks, it should be given one month's rest. In some laboratories fairly large bleedings are continued weekly, but horses so treated get out 70 of condition and do not live long.

The object of this invention is to provide a method of procedure whereby this anemia is removed forthwith, thereby allowing of 75 the more frequent and profuse bleeding of the horses or other animals.

I have found that the red cells of the blood, after the separation of the plasma therefrom, may be introduced into the blood 80 vessels of an animal from which the blood had been previously removed. These red cells are absorbed in the system of the animal together with the small quantity of plasma associated with them and the anemia to 85 which the animal is subject is thereby removed.

This invention comprises therefore the returning and the means for returning the red cells of the blood, after the separation of 90 the plasma, into the blood vessels of the animal so as to remove its anemia and increase its serum yielding capacity.

This invention is applicable to those methods in vogue as above indicated, in 95 which the cellular elements of the blood are separated from the plasma, but is not applicable to the first-described method in which the red cells become permanently entangled in the clot.

In carrying out my invention to obtain serums from the horse I proceed as follows:-

10 to 12 liters of blood are removed from the horse into large bottles thoroughly 105 cleansed and sterilized. To prevent clotting, oxalate solution (potassium oxalate preferably) is thoroughly mixed with the blood, by agitation, as the blood is running from the vein into the receiver. The bottles 110 are then permitted to stand to allow of sedimentation of the red cells. This sepa-

ration may be accelerated by the use of a centrifuge, but in the case of horse blood the centrifuge is not necessary. After the red cells have sedimented, the supernatant 5 plasma is removed into one or more suitable containers, and the remaining red cell fractions are collected into other containers known as returning bottles. These red cells by suitable means are re-injected into the 10 vein of the horse.

In order that the invention may be the better understood, reference may be made to the accompanying sheet of drawings, which illustrate the apparatus which may be used in carrying out my method, but it 15 should be understood that I do not propose to confine myself thereto.

In these drawings—

Figure 1 illustrates the bottle into which 20 the blood is first received when drawn from the animal.

Fig. 2 shows the same bottle, in which the cellular elements or red cells of the blood have been allowed to sediment. The sedimented red cells are indicated by darker 25 shading, and the supernatant plasma by lighter shading.

Fig. 3 shows the same receiving bottle, containing the red cells, connected with another bottle, into which the red cells are 30 delivered through a suitable filter.

Fig. 4 shows this last-mentioned bottle into which the filtered red cells have been received, connected with the cannula, through 35 which the red cells are returned into the blood vessels of the animal.

The apparatus illustrated in these drawings comprises three bottles or containers (or series thereof) viz., a receiving or bleeding bottle A, a plasma bottle B, and a returning bottle C. In commencing operations 40 the receiving or bleeding bottle A is provided with a stopper A' having two holes, through one of which passes a glass tube A² 45 connected by a rubber tube A³ to a cannula D. The other hole in the stopper A' is fitted with a glass tube A⁴ having a bulb containing cotton wool to act as a filter and to maintain sterile conditions.

50 The cannula D is inserted into the vein of the animal (say a horse) and the blood is withdrawn into the bleeding bottle A (Fig. 1) within which a small amount of potassium oxalate solution (or other anti-clotting 55 agent) has been placed. The bottle A is continuously agitated while the blood is running into it, whereby thorough admixture of the blood with the anti-clotting agent is secured. When the bleeding is completed 60 the cannula D is removed from the vein of the horse and is disconnected from the tube A² leading into the bottle which tube is then closed by means of a plug of cotton wool and leadfoil cap. After the sedimentation 65 of the red cells has taken place (as shown in

darker shading in Fig. 2) the stopper A' is removed from the bottle A and another stopper A⁵ is inserted therein having a downwardly projecting tube A⁶ which may be adjusted in height for withdrawing the 70 supernatant plasma leaving the red cells undisturbed. The supernatant plasma (as shown in lighter shading in Fig. 2) is then passed by means of pressure or suction through the tube A⁶ into the bottle B. A 75 lime salt is then added to the plasma in the bottle B for the purpose of clotting the same and the serum may be separated therein or more conveniently the plasma may be transferred to a separate jar in which the serum 80 is expressed from the clot in the usual way. Another stopper A⁷ is now inserted into the bottle A having a tube A⁸ which passes down to the bottom of the bottle for the removal of the red cells. This tube A⁸ is connected with a tube C' leading into the returning bottle C having a muslin filter C² through which the red cells are filtered. The pressure within the bottle A being raised, the red cells are then transferred into the 85 bottle C, or alternatively the pressure within the bottle C may be diminished, and in this way the red cells are all sucked into the returning bottle C. The bottle A is then disconnected from the bottle C, the connecting tube C' is closed by means of a stop cock C³ and the exit tube C⁴ is connected with the cannula D. Pressure is then applied to the bottle C by bellows C⁵ whereby the red 90 cells are forced into the cannula D, which is 95 inserted into the vein of the animal, and these red cells are returned to the blood vessels of the animal.

It is not necessary to add any diluting fluid to the red cells as there is a slight 100 amount of plasma left around them which is sufficient to enable this red cell fraction to flow back into the animal's vein.

The sedimentation of the red cells in the case of horse blood occurs more quickly 105 if it is allowed to take place at a warm temperature, and since it is advantageous to have the red cells at the temperature of the animal body when returning them, it is desirable to have the bottles standing during the sedimentation process at blood heat or a slightly higher temperature.

By my system I can take thirty-six liters of blood in three bleedings out of a horse in the course of five days, without producing the prolonged anemia which the extraction of ten liters of blood previously produced. The degree of anemia in the horse has been judged by red cell counts and hemoglobin percentage estimations. These 115 36 liters of blood yield slightly over 22.5 liters of plasma, whereas by the ordinary method 8 liters of blood yield about 5.2 liters of plasma, that is, 22.5 liters of plasma are obtained in five days instead of about 120 130

5.2 liters in seven days. If 10 liters of blood be taken from a horse in the ordinary way and nothing returned to the horse, the percentage fall of red cells is equal to about 5 30% depending on the size of the horse.

Under my system, after removing 36 liters of blood in five days, the percentage fall of red cells observed after the return of the red cells of the third bleeding is negligible.

10 The protein constituents of the plasma are not seriously diminished by these massive bleedings. It has been ascertained that a percentage fall from 7.8% to 7% occurred after 36 liters of blood had been extracted 15 in five days, whereas under the old system a similar fall may be found after the removal of 10 liters.

Instead of returning the red cells into the blood vessels of the animal whence they 20 came, it will be obvious that a similar result may be obtained by transfusion of the red cells obtained from one animal (after extraction of the plasma) into the blood vessels of another animal of the same 25 species which has been bled.

I claim—

1. In the manufacture of serums from animals (excluding man) the returning of the red cells of the blood, after separation

from the plasma, into the blood vessels of 30 the animal.

2. An improved method of serum production consisting of bleeding the animal (excluding man) under such conditions that clotting of the blood is prevented, separating 35 the supernatant plasma from the red cellular elements, separating the serum from the plasma, and returning the red cells to the blood vessels of the animal.

3. An improved method of serum production consisting of receiving the blood from the animal (excluding man) into vessels containing an anti-clotting agent (such as oxalate solution) allowing the blood to stand until the red cells sediment, separating 40 the supernatant plasma, adding a clotting agent (such as a lime salt) to the plasma, separating the serum from the plasma, filtering the red cells and returning 45 the red cells to the blood vessels of the animal substantially as described.

In testimony, that I claim the foregoing as my invention, I have signed my name in presence of two subscribing witnesses.

WILLIAM JAMES PENFOLD.
